CLAIM

The ornamental design for a wireless speaker with GPS display as shown and described.

DESCRIPTION

FIG. 1 is a top front perspective view of a wireless speaker with GPS display according to the present invention; FIG. 2 is a bottom front perspective view of the wireless speaker with GPS display according to the present invention;

FIG. 3 is a front view of the wireless speaker with GPS display according to the present invention;

FIG. 4 is a back view of the wireless speaker with GPS display according to the present invention;

FIG. 5 is a left side view of the wireless speaker with GPS display according to the present invention;

FIG. 6 is a right side view of the wireless speaker with GPS display according to the present invention;

FIG. 7 is a top side view of the wireless speaker with GPS display according to the present invention;

FIG. 8 is a bottom side view of the wireless speaker with GPS display according to the present invention; and,

FIG. 9 is a detailed front top perspective view of the wireless speaker with GPS display according to the present invention.

The broken line showing of the wireless speaker with GPS display is for the purpose of illustrating portions of the wireless speaker with GPS display which form no part of the claimed design.

1 Claim, 8 Drawing Sheets
